UNITED STATES PATENT OFFICE.

PERCIVAL EVERITT, OF NEW YORK, N. Y.

DESIGN FOR A SYRINGE.

SPECIFICATION forming part of Design No. 18,931, dated February 19, 1889.

Application filed January 14, 1889. Serial No. 296,296. Term of patent 14 years.

To all whom it may concern:

Be it known that I, PERCIVAL EVERITT, a subject of the Queen of Great Britain, residing at London, England, temporarily residing at New York, N. Y., have invented and produced a new and original Design for a Syringe, of which the following is a specification, reference being had to the accompanying drawings, forming part thereof.

10 Figure 1 is an elevation of the syringe and its nozzle cap or cover, showing my design; Fig. 2, a vertical section, and Fig. 3 an end view.

15 My design consists in the external shape or configuration of the syringe and its nozzle-cap.

A is the main body or tube of the syringe, which is cylindrical, but flattened and presenting the appearance of being folded or turned over at one end, as seen at a', to close 20 it up, and as shown in Figs. 1 and 2, and presenting to the eye on one side of such bottom a line parallel with but a little above the bottom line; and it has also a long nozzle at its other end (shown in dotted line) which is cov-

ered by a long thimble-like cap, B, which is 25 also cylindrical, but continuously rounded and without an angularity at its closed end c, this cap having a diameter much less than that of the tube or body A. This cap B, at its mouth or base, where it connects with the 30 tube A, is larger in diameter than the upper and main part of said cap. The exterior of this larger base is roughened or milled, as shown at d.

What I claim is—

35 The design for a syringe and its nozzle-cap herein shown and described, the same comprising the cylindrical part A of the syringe, flattened and appearing as folded over at one end, as at a', and the cylindrical cap B, having its outer end, c, continuously rounded and its other end, d, of larger diameter and with a roughened surface.

PERCIVAL EVERITT.
